FOOTSTOOL

Clara A. Ridder, Greensboro, and Byron S. Clapp, Siler City, N.C., assignors to Boling Chair Company, Siler City, N.C.

Filed Apr. 13, 1962, Ser. No. 69,696

Term of patent 14 years

(Cl. D15—8)

FIG.1

FIG.5

The side not shown is the same in appearance as the side shown.

We claim:

The ornamental design for a footstool, substantially as shown and described.
